UNITED STATES PATENT OFFICE.

VALENTINE G. SCHUCK, OF NEW YORK, N. Y., ASSIGNOR TO THE SUTRO BROS.
BRAID COMPANY, OF SAME PLACE.

DESIGN FOR BRAID.

SPECIFICATION forming part of Design No. 23,186, dated April 10, 1894.

Application filed March 5, 1894. Serial No. 502,434. Term of patent 14 years.

To all whom it may concern:

Be it known that I, VALENTINE G. SCHUCK, of the city, county, and State of New York, have invented and produced a new and original Design for a Braid to be Used by way of Ornamentation and in Trimming Garments, &c., of which the following is a full, clear, and exact description, reference being had to the accompanying drawing, showing the arrangement of the different parts, the colors of which may be varied so as to produce different effects without changing the character of the design.

It consists of two interlocked parallel cords ⁵ *a a* of uniform size, beneath which and at regular intervals there extends, outwardly, a collection or series of loops, graduated as to

length so as to describe, approximately, segments of a circle *b, b, b*, and which appear on opposite sides of the interlocked parallel cords ²⁰ at one and the same time.

The general effect of the design is that the two interlocked cords *a a* appear to pass over the center of a series of loop formed ovoidal figures which follow each other at regular intervals throughout the length of the braid. ²⁵

I claim—

A design for a braid as herein shown and described.

VALENTINE G. SCHUCK.
